ATTORNEY

UNITED STATES PATENT OFFICE

JACOB SHAPIRO, OF BROOKLYN, NEW YORK

ICE BAG AND THE LIKE ARTICLE

Application filed August 23, 1929. Serial No. 387,825.

This invention relates to ice bags and the like articles.

An object of this invention is to provide a flexible ice bag of the character described, adapted to lie flat against the body of the user, which shall be positively leakproof and comfortable in use.

A further object of this invention is to provide an ice bag of the character described, wherein the cover member is provided with a rubber washer, means for preventing looseness or accidental loss of the washer from the cover.

A further object of this invention is to provide an ice bag of the character described having means for conveniently tying the ice bag to the user's body.

A still further object of this invention is to provide a neat, compact and rugged device of the character described which shall be comparatively cheap to manufacture, comprising few and simple parts, easy to assemble, and which shall yet be practical and simple to a high degree when used.

Other objects of this invention will in part be obvious and in part hereinafter pointed out.

The invention accordingly consists in the features of construction, combinations of elements, and arrangement of parts, which will be exemplified in the construction hereinafter described, and of which the scope of application will be indicated in the following claims.

In the accompanying drawings, in which is shown one of the various possible illustrative embodiments of this invention,

Fig. 1 is an axial cross-sectional elevational view of an ice bag embodying the invention;

Fig. 2 is a top plan view of the ice bag, with parts broken away to show the interior construction; and

Fig. 3 is a fragmentary elevational axial cross-sectional view of a modified construction.

Referring now in detail to the drawings, 10 designates an ice bag embodying the invention which is seen to comprise a body 11 having a neck portion 12 for receiving a cover

14. The body 11 is preferably made of leak-proof flexible material, such as rubber, and is formed with a flat bottom portion 15 and overlapping folded portions 16 forming the top of the bag and extending inwardly to 55 provide a central opening therefor. Every portion 17 of said top portions 16 is folded upon itself and inserted in an annular member 18 of substantially U shaped cross-section forming the neck 12. Said member 18 is provided with an internally screw threaded portion 19 and parallel flanges 20 and 21 extending outwardly therefrom. The folded edge portion 17 preferably lies adjacent the screw threaded portion 19, and is tightly 60 pressed against said portion by collar 22, said collar being held in place by a downwardly folded bead 23 formed on the upper flange 20. It will be noted that the collar presses down on a portion 24 of a bag adjacent to the folded 70 portion 17 to press the same against the flange 21. This construction causes the entire top folded portions 16 of the ice bag to be substantially flat and extend outwardly. Thus the ice bag may be placed flat against the 75 body of the user, making for a more comfortable ice bag and one requiring less space, and forming a smaller bulge than the elongated ice bags now in use.

The cover member 14 may be made of sheet 80 metal or any other similar material, and is provided with an exteriorly screw threaded portion 30, adapted to co-operate with the screw threads 19 of the collar 12. Said cover is further formed with an annular depressed 85 wall 31 and another depressed wall 32, substantially at right angles thereto, forming recess 33, for receiving the annular member washer or gasket 35 adapted to be placed 90 against the collar 12 upon screwing the cover on to the ice bag. It will be noted that accidental movement, shifting or loss of the gasket is prevented, due to the recess 33 formed for receiving said washer.

For conveniently attaching the ice bag to the body of the user, a pair of diametrically opposed loops 36 are formed in the collar member 14. Said loops are provided with openings 37 for receiving ends 39 of strings, 100

cords, ribbons or the like, for tying the ice bag to the body.

In use it is merely necessary to screw the cover on to the neck or mouth of the ice bag and then to pull the strings 39 or the like around the body of the patient and tie said strings to each other, thus doing away with towels, bandages and other means now in use for attaching the ice bag to the body.

In accordance with the modified construction shown in Fig. 3 of the drawings, the ice bag 10a is provided with a top pleated portion 16a, having an inner edge portion 17a stitched as at 17b to retain the pleats. Said edge portion 17a is slightly thickened due to the superimposed folds of the pleats and is received in a neck member 12a, preferably comprising a stamped sheet metal member 18a having an internal screw threaded portion 19a and outwardly extending flanges 21a and 22a. Said flanges 21a and 22a are preferably curved or tapered and punched together to press against the edge portion to provide a leak-proof connection between said member 18a and the body 11a of the ice bag.

It will thus be seen that there is provided a device in which the several objects of this invention are achieved, and which is well adapted to meet the conditions of practical use.

As various possible embodiments might be made of the above invention, and as various changes might be made in the embodiment set forth, it is to be understood that all matter herein set forth or shown in the accompanying drawings is to be interpreted as illustrative and not in a limiting sense.

Having thus described my invention I claim as new and desire to secure by Letters Patent:

1. A bag comprising a flexible body having a pleated thickened inner edge portion forming an opening for said bag, said portion comprising superimposed folds, said inner edge portion being folded upon itself so that it tends to assume a horizontal position, a member having an internally screw threaded portion and means for gripping said folded portions to provide a leak-proof connection between said body and member.

2. An ice bag comprising a body portion made of sheet rubber having a flat bottom, the top of the bag being formed of superimposed folds and having a thickened inner edge portion, said portion being folded inwardly upon itself so that it tends to assume a horizontal position, a member having an internally screw threaded portion and means for clamping said folded inner edge portions together to provide a leak-proof connection between said body and member, and a cover for said bag having an externally screw threaded portion screwed to said screw threaded portion of said member.

3. A bag made of sheet rubber having a flat

bottom and being pleated at the top thereof, said top having an inner edge portion forming an opening, said inner edge being folded upon itself to form an annular folded edge portion so that it tends to assume a horizontal position, and an annular member having an internally screw threaded portion and a portion extending around said annular folded edge and adapted to press said folded edge portions together and against said internally screw threaded portion.

In testimony whereof I affix my signature.

JACOB SHAPIRO.
